REFRIGERATOR LATCH

Carl Geske and George Earl De Voe, Grand Rapids, Mich., assignors to Winters & Crampton Corporation, Grandville, Mich., a corporation of Michigan

Application July 13, 1935, Serial No. 31,146

5 Claims. (Cl. 292—200)

This invention relates to latches which, while not necessarily restricted as to place of use, are particularly useful when applied to refrigerators. It is an object and purpose of the present invention to provide a simple and practical latch which is substantially concealed and protected within the confines of a handle member thus making a compact and neat appearing structure.

10 An understanding of the invention and one form of structure which embodies the same may be had from the following description, taken in connection with the accompanying drawing, in which,

15 Fig. 1 is a horizontal section through the latch, and through the adjacent portions of the door and door frame on which the latch and its keeper are respectively mounted.

Fig. 2 is a section substantially on the plane 20 of line 2—2 of Fig. 1.

Fig. 3 is a section substantially on the plane of the broken line 3—3 of Fig. 1.

Fig. 4 is a view similar to Fig. 1, showing the position of the parts on manual operation of the 25 latch when the door is opened, and

Fig. 5 is a perspective view of a detail of the latch structure, comprising the main supporting element thereof and which is to be secured at the free vertical edge of the door.

30 Like reference characters refer to like parts in the different figures of the drawing.

The refrigerator door 1 is adapted to close a door opening which is surrounded by a door frame or casing 2. The door at its free edges has a narrowed ledge 3 which extends a short distance over the adjacent faces of the door frame members. At the inner side of the ledge a suitable yielding cushion member 4, preferably of rubber, is attached so that when the door is closed, a tight seal is provided against the escape of refrigerated air or the entrance of heat.

40 In the construction of the latch member, which is to be attached to the free vertical edge of the door, a supporting bracket is provided, the structure of which is shown in Fig. 5. It comprises a plate having oppositely extending ears 5 and with spaced apart arm supports 6 extending at right angles thereto to one side, the same terminating at their outer ends in hooks 7. The plate referred to is completed by an intermediate flat member 8, which extends beyond the outer edges of the ears 5, and which is bent laterally to form an upper lip 9 at its upper end and a short flange 10 at its lower edge. This supporting member is attached directly at the edge of the door ledge 3 by means of screws 11 which pass through the ears 5 and thread into the door as shown.

45 A pivotally mounted latch bolt 12 of irregular shape is located between the supporting arms 6.

At its inner end it is formed with a latching head 13 spaced from which is a strike lug 14, there being a slot 15 between the parts 13 and 14 into which the engaging portion of a strike plate enters when the door is closed. At its outer end and opposite side a short stop lug 16 is provided, which in one position of the latch bolt, as shown in Fig. 1, is adapted to come against the face of the plate 8.

50 A pivot pin 17 passes through the supporting arms 6 adjacent their corners as shown, and also through the latch bolt 12. In practice a thin sleeve 18 of metal surrounds the pivot pin, which at its ends passes through the sides 19 of a sheet metal operating handle 20. The ends of the pivot pin are headed or riveted over as shown in Fig. 2, thus assembling the handle inseparably with the latch mechanism described. The handle is substantially a sheet metal shell which houses the major portion of the mechanism described and which at one end is formed with a pressed out ledge 21 adapted to come against the outer side of the lug 14 on the latch bolt, as shown in Figs. 1 and 3, whereby by pulling outwardly on the free end of the handle the latch bolt is turned in a counterclockwise direction from the position shown in Fig. 1 to that shown in Fig. 4.

55 The latch bolt is acted upon by a spring 22 which is mounted between the widened heads of two bars 23 passing through the spring and slideable over each other. One of the bars is seated against the hook 7 and the other in a recess in the outer end of the bolt 12. The spring, in the movements of the bolt from the position shown in Fig. 1 to that shown in Fig. 4, has its line of force carried across the pivotal axis of the pivot pin 17, and, therefore, operates to hold the latch bolt in either position to which it is moved. The extreme positions of movement of the latch bolt are governed by the engagement of the stop lug 16 against the part 8, as previously described, and by the edge of the bolt coming against the lip 10, as shown in Fig. 4.

60 The door frame member 2 is recessed at 24 and a housing member 25 of thin metal is mounted in the recess. The housing member is open at its outer side and is covered by a strike plate 26 which is secured in place by screws 27 (Fig. 2). The strike plate has an opening through which the headed end 13 of the latch bolt may pass; and it is formed at one side of the opening with a strike portion 28 which, in the closed position of the latch in Fig. 1, is received in the recess 15 of the latch bolt and bears against the side of the head 13 adjacent said recess. For sake of appearance the strike plate 28 is equipped with a covering plate 29 of thin metal.

65 When the door is closed, as in Fig. 1, the

head of the latch bolt 13 engages with the portion 28 of the strike plate and is yieldingly held in such position by the force of spring 22, thereby serving to compress the sealing member 4 sufficiently to provide an air-tight seal between the door and the door frame. To open the door the handle 20 is manually operated from the position shown in Fig. 1 to that shown in Fig. 4. The ledge 21 on the handle, engaging against the lug 14, turns the latch bolt until the line of force of the spring 22 crosses the pivotal axis of the pin 17, whereupon the spring continues the rotative movement of the dog until said bolt is stopped by engaging against the lip 10. In such position the head of the bolt is free to pass outwardly through the opening in the strike plate 26.

On closing the door, the latch bolt, being in the position shown in Fig. 4, lug 14 comes against the strike part 28 causing the bolt to be turned in a clockwise direction until the line of force of spring 22 passes back across the axis of pivot 17, whereupon the spring turns the bolt into operative engaging position with the strike plate as shown in Fig. 1. The action of the latch is easy and relatively sensitive so that no great force is required to either operate the latch for opening the door or in pushing the door shut so as to cause the latch to hold the door closed. There is indicated in Figs. 1 and 2 a push rod 30 which, when moved longitudinally to the right and engaging against the head 13 of the latch bolt, may turn the latch bolt from its closed position in Fig. 1 to the open position in Fig. 4. This is designed to be operated by a foot pedal mounted adjacent the lower part of the refrigerator, but as the mechanism for thus operating it is no part of the present invention it is not specifically illustrated and described.

It will be noted that the head 13 has a rounded cam-like edge so that should the latch bolt, when the door is opened, be accidentally or otherwise moved from the position in Fig. 4 to that in Fig. 1, such cam edge of the door will ride against the inner edge of the strike portion 28, whereby the door may be readily closed under such conditions.

The invention is of a very practical and meritorious character and has so proven in practice. It is economical to produce, the assembly of the parts is easy and the application of the same to a refrigerator door is convenient and easy, and when secured in place the appearance is pleasing and attractive.

The invention is defined in the appended claims and is to be considered comprehensive of all forms of structure coming within their scope.

60 We claim:

1. A latch comprising, a support including a base plate and with spaced arms extending therefrom, a latch bolt pivotally mounted between the arms, said bolt having a stop thereon adapted to engage against the base plate in one extreme position of pivotal movement, a hollow handle pivotally mounted upon the same pivot as the latch bolt and housing a portion thereof, said handle being adapted to engage the latch bolt to turn it in one direction, and spring means housed within the handle and acting on

the latch bolt for yieldingly holding the latch bolt in either of its extreme positions of pivotal movement.

2. In a latch structure, a support comprising a base plate, spaced apart arms extending at right angles from said plate, said arms having extensions thereon to one side of the adjacent edge of the plate hooks on said extensions, a latch bolt pivotally mounted between said arms and adapted to engage against said base plate between said arms at extremes of its pivotal movement, said latch bolt having a keeper receiving recess in one edge thereof, a unitary sheet metal hollow handle extending over said arms and the extensions thereof and partly over said latch bolt and engaging against the latch bolt to turn the same in one direction, said handle being pivoted to turn about the same pivotal axis as the latch bolt, and compressible spring means between the latch bolt and the hooks yieldingly holding said bolt in either of the extreme positions to which it is turned, said hollow handle housing the compressible spring means and hooks at all times.

3. In a latch structure, a pivotally mounted latch bolt, a support therefor, a ledge on said support, a hollow handle pivotally mounted on the same pivot, said handle having spaced apart sides and extending over said pivot and partly over the latch bolt, spring means acting on the latch bolt to resist turning movement thereof and positioned so that its line of force crosses the pivotal axis of said pivot when said latch bolt is turned, means on the handle engaging the latch bolt for turning the same in one direction, and interengaging means, including said ledge, on the latch bolt and its support for limiting the turning movement of the latch bolt in either direction, said handle being of sufficient size to completely house the said spring means whenever the handle is in either of its extreme positions.

4. A latch comprising, a base plate, a fixed extension on said base plate, a latch bolt pivoted to said extension, spring actuated means co-acting between said fixed extension and said latch bolt and a hollow handle pivoted to said extension and associated with said latch bolt for manually actuating the same, said fixed extension and said spring actuated means and a considerable portion of said latch bolt being housed within said handle at all positions of movement of said handle.

5. In combination with a door and a door frame therefor, of a latch including a plate secured to the edge of the door, spaced apart arms projecting from said plate away from the edge of the door, a latch bolt pivotally mounted between said arms, said latch bolt having a keeper receiving recess in an edge thereof, a hollow pivotally mounted handle for turning the latch bolt in one direction about its pivot and spring means acting to hold the latch bolt yieldingly in either of its two extreme positions of movement, said hollow handle receiving and concealing the spaced apart arms and the said spring means whenever the latch is in either of the extreme handle positions.
